UNITED STATES PATENT OFFICE.

PATRICK A. HALEY, OF CLEVELAND, OHIO.

STEEL TIE AND RAIL-JOINT.

946,696.

Specification of Letters Patent. Patented Jan. 18, 1910.

Application filed January 27, 1909. Serial No. 474,528.

To all whom it may concern:

Be it known that I, PATRICK A. HALEY, a citizen of the United States, residing at Cleveland, in the county of Cuyahoga and 5 State of Ohio, have invented new and useful Improvements in Steel Ties and Rail-Joints, of which the following is a specification.

My invention relates to improvements in railway ties.

10 The primary object of the invention is the provision of a metal tie which shall be of such construction that it may be manufactured by a rolling process, whereby to enable the tie to be manufactured and sold at 15 a cost no greater than the cost of a wooden tie.

A further object of the invention is the provision of a rail joint which will prevent the creeping of the rails one with relation 20 to the other, and the provision of means for fastening the rails at the joints to the ties which will prevent the rails from creeping with relation to the ties.

With the above and other objects in view 25 the invention consists in the construction, combination and arrangement of parts hereinafter fully described and claimed, and illustrated in the accompanying drawing, wherein:

30 Figure 1 is a sectional view of a tie, rail joint and rail fastening constructed in accordance with my invention. Fig. 2 is a top plan view thereof. Fig. 3 is a view in end elevation of the tie. Fig. 4 is a view 35 similar to Fig. 1, illustrating a modification of the rail fastening. Fig. 5 is a sectional view taken on a plane extending transversely through one of a pair of rails connected with a joint constructed in accordance with my invention. Fig. 6 is a perspective view of a fragmentary portion of 40 one of the fish plates of the rail joint.

Referring to the drawing by reference numerals, 1 designates the top, and 2 the sides 45 of a hollow railway tie constructed in accordance with my invention the ends of the tie being fully open. The tie is constructed of metal, and the sides 2 thereof incline outwardly and downwardly, terminating in 50 horizontally disposed flanges 3. The sides 2 of the tie are held against lateral distortion by means of straps 4 which are formed with overhanging lips 5 having interlocking engagement with the flanges 3 of the

tie. The straps 4 are secured in applied 55 position by means of bolts 6 or their equivalents. The top 1 of the tie is provided with a plurality of openings 7 through which pass the bolts by which the track fastenings are secured to the tie. To permit the application and removal of the bolts, the sides 2 of the tie are provided with hand holes 8. The bolts may also be applied and removed through the open ends of the tie.

The rail joint comprises a pair of fish 65 plates 9 which are secured to the opposite sides of the webs 10 of the rails by bolts 11. On their inner sides the fish plates 9 are provided with annular projections 12 which surround the bolt receiving openings 13, 70 said projections fitting in corresponding depressions 14 in the webs 10 of the rails and preventing the rails from creeping one with relation to the other. The rails are secured to the tie at their joints by means of track 75 fastenings 14 which are secured to the tie by bolts 15, said bolts passing through the openings 7 in the top 1 of the tie and may be applied from the open ends of the tie or through the hand holds 8. The 80 under sides of the track fastenings 14 are recessed as at 16 to receive the flanges 17 of the rails. At their inner sides the track fastenings 14 are formed with lugs 18 which fit in openings 19 in the fish plates 9, said 85 lugs preventing the rails from having any movement with relation to the ties. The track fastenings are provided on their upper sides with strengthening ribs 20. These track fastenings are only used at the joints 90 of the rails. The track fastenings used at other points in the length of the rails are not provided with the lugs 18. At such points where it is found impossible to use these track fastenings track fastenings such 95 as 21 are used. The track fastening 21 is provided at one end with an overhanging lip 22 which engages one of the flanges of the rail. The track fastening is mounted in a recess 23 formed in the top 1 of the 100 tie and is secured in position by means of bolts 24.

It should be apparent from the above description taken in connection with the accompanying drawing, that I provide a metal 105 tie which is simple, durable and efficient, which may be manufactured by a rolling process, and which may be manufactured

and sold at a comparatively low cost. It should also be apparent that the rail joint and track fastening are simple, durable and efficient, and that they may be manufactured and sold at a comparatively low cost.

As the rail joint prevents the rails from creeping one with relation to the other, and as the track fastening prevents the rails from creeping with relation to the ties, the contraction and jar of the rails will not separate the rails at their meeting ends. The rail joint and track fastening cannot in any way interfere with the expansion and contraction of the rails.

While I have described the method of operation of the invention, together with the apparatus which I now consider to be the best embodiment thereof, I desire to have it understood that the apparatus shown is merely illustrative and that such changes

may be made when desired as are within the scope of the appended claim.

Having thus described the invention, what is claimed as new is:—

The combination with a tie and with a 25 pair of rails provided with depressions in their webs, of fish plates secured to the webs and provided on their inner sides with projections which fit in the depressions, said fish plates being provided with openings, 30 track fastenings provided on their inner sides with lugs which fit in the openings in the fish plates, and means securing the track fastenings to the tie.

In testimony whereof I affix my signature 35 in presence of two witnesses.

PATRICK A. HALEY.
